MULTIRANGE RECEIVER

Alfred A. Linsell, Sydenham, London, England,
assignor to Radio Corporation of America, a
corporation of Delaware

Application April 13, 1936, Serial No. 73,989
In Great Britain April 26, 1935

3 Claims. (Cl. 250—20)

This invention relates to radio receivers and more particularly to multi-range tunable receivers adapted to receive over different wave length ranges.

5 Broadcast receivers for sound and music signals are at present in widespread use and it is common to construct such receivers to be tunable over two wave length ranges corresponding respectively to the so-called medium wave broadcast range (at present from about 250 to 550 meters) and to the so-called long wave broadcast range (at present from about 900 to 1900 meters). It is expected, however, that there will shortly be established in Great Britain a public 10 service of television transmission upon short waves—probably upon waves in the neighborhood of 7 meters long—and the object of the present invention is to provide an improved economical and easily operated receiver which can 15 be employed for broadcast reception over a plurality of wave length ranges of which one includes a short wave range for television signals.

The problem of extending a radio receiver which has been constructed to receive sound signals on the ordinary present broadcast waves so 20 that it may receive also television signals on short waves involves more than merely making provision for the reception of signals within the further short wave range, for it will be appreciated that the width of frequency spectrum occupied by television signals is much more than that occupied by sound signals. Sound signals can be (and by international agreement at the 25 present time are) accommodated within a band of frequencies equal to the carrier $\pm 5,000$ cycles, but the modulation frequency range involved in television may easily extend up to 2 megacycles or more.

For the purpose of convenience in description, 30 radio receiving apparatus adapted to receive carrier frequency energy modulated with sound or music signals, will be hereinafter referred to as "sound broadcast receiving apparatus".

According to the main feature of this invention 35 a radio receiver capable of receiving over a plurality of wave length ranges of which one is a short wave television range, comprises sound broadcast receiving apparatus preceded by a heterodyne arrangement adapted to transform 40 received short wave television modulated signals into a modulated intermediate carrier frequency and means intended to be actuated when the receiver as a whole is switched over to receive short wave television modulated signals, are provided 45 for broadening the modulated carrier frequency

channel or channels in the sound broadcast receiving apparatus to the extent necessary to enable said channel or channels to pass the relatively wide band occupied by television signals and for fixing the tuning of the said broadcast 5 receiving apparatus at a predetermined value corresponding to said intermediate frequency. Thus, although a radio receiver in accordance with this invention may be left, after sound broadcast reception, with the controls for the 10 variably tunable carrier circuits of the sound broadcast receiving apparatus anywhere within the range of variation (e. g. anywhere between 250-550 meters or 900-1900 meters depending upon the wave length upon which sound broadcast reception has been last effected) the arrangement is made such that when the receiver is changed over to television reception said circuits are tuned to a predetermined frequency 15 chosen as the intermediate frequency for such 20 reception.

Where the reception of low definition television signals—i. e. television signals which do not occupy a width of spectrum materially different from that occupied by a sound program—25 is contemplated, it is not necessary to broaden the carrier frequency channel or channels in the sound broadcast receiving apparatus for such apparatus will serve, unaltered, for low definition television.

30 The invention is illustrated in the accompanying drawing wherein Figure 1 shows diagrammatically a portion of a receiving circuit embodying the invention, Figure 2 shows a form of indicating dial that may be used, and Figure 3 shows the tuning control for the receiver and the cooperation therewith of the band switching means.

Referring to Figure 1 the radio receiver is 35 shown to comprise a short wave receiving aerial 40 which is coupled to the variably tunable input circuit 2 of a frequency changer stage 3 to which is also applied high frequency local oscillatory energy from a variably tunable local oscillator 4. The frequency changer and local oscillator 45 may be constituted by the same valve as well known, per se, or as indicated in the drawing, separate local oscillator and frequency changer valves may be provided. The tuning controls for the local oscillator and the input circuit of the 50 frequency changer are preferably gang controlled from a common handle as indicated by the line 5. Beat frequency energy from the frequency changer is applied (after further amplification, if desired) to the input circuit of the 55

sound broadcast receiving apparatus which input circuit thus serves as a beat frequency circuit for television reception on short waves. This input circuit may consist of a coil 6 included in the grid cathode circuit of a valve 7 and arranged to be shunted (for sound reception on broadcast waves) by a tuning condenser 8 adapted to tune said coil over the sound broadcast wave length range in question. The said tuning condenser is in series with switch contacts 9, 10, which are opened when the receiver as a whole is to receive short wave television signals, the switch 8 being, in these circumstances, moved into a position (the position shown) in which the tuning condenser is cut out of circuit and instead there is shunted across the coil 6 a small fixed condenser 11 shunted by a resistance 12. This combination 11, 12, is put in circuit for short wave reception through contacts 13, 10. The small fixed condenser 11 is of such magnitude as to tune the coil 6 to a predetermined fixed frequency corresponding to the beat frequency from the frequency changer 3 and the resistance 12 is of such magnitude as to make the coil 6 when thus tuned, sufficiently flatly tuned to pass the range of television modulation. For sound broadcast reception an ordinary broadcast aerial 14 is coupled to the coil 6 and the switch 8 is moved into that position (not shown) in which the said coil 6 is tuned by the variable condenser 8 and the combination 11, 12, is out of circuit.

In the receiver illustrated in Figure 1 the sound broadcast receiving apparatus is itself of the superheterodyne type and accordingly the output of the valve 7 is mixed with local oscillations from a second local oscillator 4' and applied to the input circuit of another frequency changer valve 14. This input circuit is arranged in similar manner to the input circuit of valve 7 and includes a switch 8' having contacts 9', 10', 13' which in one position causes said input circuit to be tunable by a variable condenser 8' over the desired sound broadcast wave range and to have a narrow pass range while in the other position the switch open-circuits the tuning condenser and switches in a small condenser and shunt resistance combination 11', 12' which fixedly tunes the input circuit coil 6' to the predetermined frequency and gives it the desired wide pass range. The output from this mixing valve 14 is coupled to a fixed tuned further intermediate frequency amplifier as in the usual way. Each of the intermediate frequency tuned circuits of this amplifier (only the first stage of the said amplifier is illustrated, this stage including the valve 15) is shunted by a resistance 16 when the switch 8'' is in the position shown contacting switch contacts 17, 18, for television reception so that each resistance 16 broadens the pass range of its associated circuit sufficiently for the television signals. All the other intermediate frequency stages (if any) are like that illustrated and therefore it is not thought necessary to show such further stages nor the rest of the receiver which is as well known per se, and includes the necessary demodulating and translating apparatus together with filters and/or change-over switches for enabling television or sound reproduction to be effected.

It will be seen that in Figure 1 for short wave television reception, the variably tunable carrier stages of the sound broadcast receiving apparatus are fixed tuned to a predetermined frequency, and act as intermediate frequency stages

as respect the incoming short waves, while the pass band of the carrier stages of the said sound broadcast receiving apparatus is widened to pass the television signals. For sound reception on broadcast waves the said sound broadcast receiving apparatus operates in the normal manner. Preferably all the switches above described are gang controlled, indicated schematically by the dash line 26, with a switch a which, in the sound reception position, switches in the broadcast receiving aerial 14 so that for television reception the operator has merely to throw the switch control into the position appropriate to television reception and then effect tuning merely by varying the control handle to which the tuning reactance of the first local oscillator 4 and that of short wave tuned circuit (or circuits) are ganged. Only one such short wave tuned circuit is actually shown, namely the circuit 2.

In the embodiment of Figure 1 when television reception is to be effected the variably tunable carrier stages of the sound receiving broadcast apparatus are fixed tuned to a predetermined frequency by connecting small shunt condensers 11, 11' thereacross. The provision of such shunt condensers is not, however, necessary and by suitable design the self-capacities of the inductances (6, 6') in the tuned circuits in question may be caused fixedly to tune the said circuits to the desired predetermined frequency.

In the modification partly illustrated in Figures 2 and 3 wherein the variably tunable carrier circuits of the sound broadcast receiving apparatus are converted into fixedly tuned intermediate frequency carrier circuits for television reception, the required fixed intermediate carrier frequency tuning is obtained without the need for providing any switches affecting the tuning of the stages in question, but merely by so arranging the tuning controls as to ensure that for television reception the circuits in question are tuned by their normal controls to a predetermined frequency, preferably the lowest frequency in their tuning range. For example in a receiver wherein the variably tunable carrier stages of the broadcast receiving apparatus are tuned each by a variable condenser in a "gang" of condensers operable by a common control knob the "gang" shaft which is operated by a knob 22 carries a pointer 19 moving over a scale 20 marked with the broadcast tuning range (for example 250 to 550 meters) and there is provided an additional mark 21 on the scale below the "250 meters" mark this additional mark being labelled "Television". A convenient arrangement is shown in Figure 3 in which the tuning knob 22 drives the "gang" shaft 23 through a friction clutch 24 and the said gang shaft has a limit stop 25 for the minimum capacity position which position is reached when the pointer is between the "250 meter" mark and the "Television" mark. Accordingly, for television reception the tuning knob is rotated until the pointer 19 (not shown in Figure 3) points to the "Television" mark and this ensures that all the condensers will be in their minimum capacity positions as shown. The "gang" shaft 23 carries a switch operating member 26' so arranged that when the knob 22 is moved to the position for television reception, the necessary resistances are switched into the carrier circuits of the sound broadcast receiving apparatus to broaden the acceptance band thereof to the extent necessary for television reception.

Although in the above described embodiments the use of shunt resistances for the purpose of broadening the acceptance band of the sound broadcast receiving apparatus is referred to, obviously other expedients known per se, may be resorted to without departing from the spirit and scope of the appended claims.

Having now particularly described and ascertained the nature of my invention and in what manner the same is to be performed I declare what I claim is:

1. A receiving system for the selective reception of sound signals transmitted on a carrier within the broadcast band and of television signals transmitted on a carrier within a widely separated frequency band, comprising a vacuum tube amplifier having an input circuit tunable to desired frequencies within the broadcast band and capable of passing a narrow range of modulation frequencies, said input circuit being constituted by an inductance and a variable condenser, and means for converting said tunable input circuit to a fixedly tuned circuit which is resonant to a frequency within said widely separated frequency band for television signals and which is capable of passing a range of modulation frequencies several times wider than the range of modulation frequencies passed by the tunable circuit in the reception of sound signals, said fixedly tuned circuit being constituted by said inductance and a parallel combination of a resistance and a capacity connected in shunt to said inductance, said converting means comprising switch means for selectively connecting in shunt to the inductance the variable condenser or the parallel combination of said resistance and capacity.

2. A receiving system for the selective reception of sound signals transmitted on a carrier within the broadcast band and of television signals transmitted on a carrier within a widely separated frequency band, comprising a vacuum tube amplifier having an inductance connected to the input electrodes thereof, a variable condenser adapted to be connected across said inductance to

form therewith a circuit tunable to desired frequencies within the broadcast band and capable of passing a narrow range of modulation frequencies, a fixed condenser and a shunt resistance adapted to be connected across said inductance to form therewith a fixedly tuned circuit which is resonant to a frequency within said widely separated frequency band for television signals and which is capable of passing a range of modulation frequencies several times wider than the range of modulation frequencies passed by the tunable circuit in the reception of sound signals, and means for selectively connecting said variable condenser or said fixed condenser-resistance combination across said inductance.

3. A receiving system for the selective reception of signals transmitted in widely different channels of the frequency spectrum, such as for example, a sound signal channel having a carrier in the broadcast band between 250 and 550 meters and requiring modulation frequencies of about 10 kc. wide, and a television signal channel having a carrier below about 100 meters and requiring modulation frequencies several times wider than those of the sound signal channel, comprising a conventional sound broadcast receiver provided with at least one resonant circuit constituted by an inductance and a shunt variable condenser which are tunable to a frequency within the broadcast band and are capable of passing only a limited band of modulation frequencies, a circuit responsive to television signals in a channel below 100 meters coupled to said sound receiver, means adapted to cooperate with said inductance of the sound receiver to resonate at a frequency in said short wave channel and to pass the relatively wide band of modulation frequencies occupied by the television signals, and switching means constructed and arranged to selectively cut in one or the other of the means resonating with the inductance depending upon whether sound or television signals are desired to be received.

ALFRED A. LINSELL.
